UNITED STATES PATENT OFFICE.

HARRY G. CARTER, OF NORTHFIELD, NEW HAMPSHIRE.

BUSINESS-RECORD AND INCOME-TAX BOOK.

1,350,854.

Specification of Letters Patent. Patented Aug. 24, 1920.

Application filed February 7, 1920. Serial No. 356,960.

To all whom it may concern:

Be it known that I, HARRY G. CARTER, a citizen of the United States, residing at Northfield, in the county of Merrimack and State of New Hampshire, have invented certain new and useful Improvements in Business-Record and Income-Tax Books, of which the following is a specification.

The primary object of my invention is the provision of a book for keeping accounts of merchants by which the merchant is provided with a simple and practical method of assembling certain essential statistics pertaining to the conduct and condition of his business, and in such manner as will enable him to review at weekly intervals its progress and status from all essential aspects.

Another object is the provision of means whereby the weekly accounts can be assembled to provide an annual recapitulation of the year's business.

A further object is the provision of columns for the arrangement of the recapitulation data in such a way that the same may be conveniently transferred to a sheet having a form similar to the United States Government income tax return.

The sheets of my book are related to each other and each of the columns which does not contain original entries, has a reference to the column from which its data is taken.

A brief description of the preferred embodiment of my invention and its use is as follows:

The account sheets of the book are of four different kinds. The first sheet contains the merchandise account in two sets of columns, one set for the merchandise received according to the invoices, and the other set for the invoices settled. In my preferred embodiment one of these merchandise account sheets is provided for each week of the year. With each merchandise account sheet is a second companion sheet containing the summary of the first sheet by columns, "Accounts payable," "Merchandise stock on hand," "Record of sales," "Accounts receivable," "Cash account," "Cash drawn by owners," "Profit and loss account." The third sheet is a recapitulation sheet for the year on which is entered the totals from the accounts on the respective second sheets, one line being provided for

the summaries of each week's accounts, 55 there being fifty-two (52) such lines on the page and a footing line below giving a summary for the entire year. The headings of the columns on this sheet are arranged in groups, the merchandise and cash accounts 60 being in one group, the expenses deductible for income tax return in another group, and the expenses not deductible for income tax return in a third group. The fourth sheet contains the accounts which are made 65 up at the end of each year such as weekly prorata of overhead expense, summary of inventories, extract from income tax return, percentage statistics. In addition the table giving the rate of income tax on net income, 70 is shown.

I will now describe my invention in detail.

Referring to the drawings wherein the figures represent views of sheets or portions 75 of sheets having accounts thereon.

Figure 1 represents the "merchandise account."

Fig. 2 represents the account for "net merchandise received."

Fig. 3 is the "accounts payable."

Fig. 4 is the "merchandise stocks on hand."

Fig. 5 is the "record of sales."

Fig. 6 is the "accounts receivable."

Fig. 7 is the "cash account."

Fig. 8 is the account of "cash drawn by owners."

Fig. 9 is the "profit and loss account."

Fig. 10 is the "recapitulation of business 90 for the year."

Fig. 11 is the "weekly pro-rata overhead expense."

Fig. 12 is the "summary of inventories."

Fig. 13 is the "extract from United States 95 income tax return form 1040."

Fig. 14 is the "percentage statistics."

Fig. 15 shows the "rate of income tax on net income."

As merchandise is received into stock and 100 checked by invoice the date of invoice, name of dealer, consecutive number, gross amount of invoice and amount of freight, express and hauling are entered in the left portion, of the merchandise account, Fig. 1. 105

When an invoice is paid either in full or in part, the date, name of dealer, invoice number (as shown in column 1) are entered

on the right portion of the page, the partial settlements or complete settlement being indicated by "P/S" or "C/S" respectively.

The gross amount of the invoice, or that portion settled, should be entered in column 3 and deductions made under columns 4, 5, 6 and 7 where allowances are made for "freight and express," "merchandise claims," "merchandise returned" or "cash discount," respectively. The actual cash paid is entered in column 8 under "Net amount paid." Obviously the sum of the amounts of columns 4, 5, 6, 7 and 8 should equal the entry in column 3. When the invoice is paid by check the check number is entered in the last column.

When merchandise is received "C. O. D." or purchased for cash, entries are made on both sides of the merchandise account in order to assure accuracy of "merchandise stock on hand," column 12, Fig. 4, and "merchandise received," column 9, Fig. 2.

At the end of each week or whenever the account is closed for the particular sheet of Fig. 1, the total of column 3 should balance with the sum of the totals of columns 4, 5, 6, 7 and 8.

Referring to Fig. 2, "Net merchandise received this week," the entry for column 9 in line 1, "Merchandise received from dealers," is taken from the total at the bottom of column 1, as indicated on that line. Line 2, "Merchandise received on account from customers," is used for the entry of the total amount of goods or produce which has been received for that week, on account from customers. In this account the market value of the commodity is used and not necessarily at the credit price allowed to the customer. The merchandise delivered to the customer in exchange for produce or other commodity should be included in "Charge sales," column 15, Fig. 6. In this manner the profit on the transaction is included in the profit and loss account and also appears in the annual recapitulation of business, Fig. 10, and the income tax return, Fig. 13. Line 3, the total of column 2 for "freight express and hauling" is added and the total extended to column 10.

In column 9 the items to be deducted as "freight and express allowed," column 4; "merchandise claims allowed," column 5; "merchandise returned to dealers," column 6, and "cash discounts," column 7, are added and the total extended to column 10. The difference is the "net merchandise received this week."

Referring to Fig. 3, the "net merchandise liability" of line 1 is brought forward from the total at the bottom of column 11 of the previous week. To this is added the merchandise received for the week taken from column 1, as indicated. From the total of these two is deducted the "merchandise

bills settled" from column 3, the difference being the "net merchandise liability."

Referring to Fig. 4, the "merchandise on hand" is taken from column 12 of the previous week, the "net merchandise" received this week from column 10 and the "merchandise returned by customers, at cost," from column 13, are totaled. From this total is deducted the "merchandise sales for the week, at cost" from column 13. The difference is the "merchandise stock on hand at close of week."

In Fig. 5, the "record of sales" is kept, the cash and charge sales, being entered at the close of each day's business for that day in columns 14 and 15 respectively. In column 17 is entered the "cash received on account" for the day. The total cash and charge sales are entered in column 16 and from this total deduct the markup percent. of profit. The result is the approximate cost of merchandise sold and should be entered in column 13, "Cost of merchandise." At the end of the week the sales for the week are totaled and to this total the "grand total sales" figure at the bottom of column 16 of the previous week is added, which gives the "grand total sales to date."

Fig. 6 shows the "accounts receivable." The amount "due from customers last week" is obtained from column 19 of the previous week. To this is added "charge sales" for this week from column 15. Deductions are made for "cash received on account for week" from column 17, "discounts and allowances to customers," "merchandise returned by customers," "worthless (canceled) accounts" and the difference is the "net due from customers this week." Below this is placed the "net due from customers last week" and the difference between these two shows the increase or decrease over last week.

Fig. 7 shows the "cash account." On the "debit" side of the account are added, the "bank balance" brought forward from column 22 of the previous week, "cash on hand" from column 22 of previous week, "cash sales for this week" from column 14, "cash received on account" this week from column 17, "miscellaneous cash receipts" this week (itemized). On the "credit" side of the account are added "net merchandise bills paid for week" taken from column 8, "expense items not pro-rated," "cash drawn by owners" from column 24, "pro-rated (overhead) expense" from column 23, "barters," "fixtures and additional equipment." The total is the disbursement for the week. To this total is added the bank balance and cash on hand at end of week which gives the balance for column 29.

Fig. 8 shows the "cash drawn by owners" giving name and amount drawn, the "total to date" of last week is entered under

- "brought forward" to show the amount drawn to date by that person. This account, column 24 is used in the cash account to which reference has already been made.
- 5 Fig. 9 shows the "profit and loss account." In column 25 the "cost of merchandise sold" from column 13 is deducted from the "total sales for week" from column 16 which gives the gross profit for the week. This total is 70 extended to column 26. From this is subtracted the total of "merchandise returned by customers" from column 18, "discounts and allowances to customers" from column 18, "worthless accounts" (canceled this week) from column 18, "expense items (not pro-rated)" from column 21, "weekly pro-rated expense" from column 28, Fig. 11. This gives the net merchandise "profit or loss for week," the profit being entered in 75 black and the loss in red. Below this in column 26 is entered the "cash discounts for the week" from column 7. This is added if there is a "net profit" and subtracted from a "net loss." This total or difference gives 80 the "total net profit or loss for week." From this is deducted the "property losses by fire, flood, theft, etc." The "total net profit or loss from last week," taken from the bottom of column 26 is added which gives the 85 90 "grand total net profit or loss to date."
- Fig. 10 is the "recapitulation of business for the year." This sheet contains one line for each interval of time covered by the accounts of Figs. 1 to 9. If the accounts of Figs. 1 to 9 are closed each week, there will be 52 lines in the recapitulation sheet of Fig. 10. If the accounts of Figs. 1 to 9 are closed each three days the recapitulation sheet will have 104 lines, and so on.
- 95 40 Referring to the headings of Fig. 10 it will be seen that the main headings fall in three large groups. The first group contains the "merchandise and cash accounts," the second group contains the "selling expenses," including all items which are deductible for income tax return. The third group contains the expenses which are not deductible for income tax return. This grouping of these items has special relation to the United States income tax return, a form similar to which is included in my book and which will be later described.
- 50 It is to be noted at the outset that the columns of this sheet like the other columns and lines in my book which do not contain original entries, have indicia giving information from where the amounts for the entries are to be taken. At the end of each week or interval of time covered by Figs. 1 to 9, entries are made on a line across the sheet for that week or interval of time according to the indicia of the respective columns denoting the column from which the entry is to be taken.
- 60 65 The left hand column is for the date of

the ending of the week or other interval of time covered by the accounts of Figs. 1 to 9. In column A is entered the "net cost of merchandise received for sale" which is taken from column 10, Fig. 2. Columns B, C, D and E cover the "merchandise sales" and entries are made from columns 16 and 18 for columns B, C and D as indicated, the amount for entry in column E being found by deducting the total of columns C and D from column B. Column F carries the "miscellaneous cash receipts" which is taken from column 20 opposite the line bearing that title in Fig. 7. 75

Columns G to W covering the "selling expenses" which are deductible for income tax returns are so arranged that the totals under these columns may be transferred conveniently and in order to the income tax return, Fig. 13, to be later described in 80 its relation to these columns. It is also to be noted that the arrangement of the items in Fig. 7 is such that the transfer of amounts from the "cash account" to Fig. 10 in columns G to T is facilitated. In column U is placed the total for the line in columns G to T. Columns V and W carry the "property losses" from column 26 and the "worthless accounts" from column 18, respectively. 90

95 Columns X, Y and Z carry the amounts for items which are not deductible for income tax return. The amounts for these columns are obtained from column 2, Fig. 1, and column 22, Fig. 7, as indicated at the 100 head of the column. The amounts in column X are listed as non-deductible since they have already been deducted in column A.

Fig. 11 shows the "weekly pro-rata of 105 overhead expense" as estimated for the present year and based upon known results from the recapitulation sheet of the previous year with any changes which it is known will occur during the present year such as 110 increased rent, increased rate on lighting, etc.

The amounts in column 27 for the year is divided by 52 (weeks) and the result entered in column 28. Except as there is 115 an increase or decrease in fixed overhead charges during the year, the totals of column 28 will remain unchanged for weekly entry to "profit and loss account," column 25, Fig. 9. 120

In Fig. 12, "summary of inventories" shows the difference between the values in merchandise on hand at beginning of year and end of year as shown by the inventories.

Fig. 13 shows a form similar to form 1040, 125 United States income tax return with the addition of indicia to denote where the amounts to be entered will be found. Referring to these by line number 1, "Gross sales and income from business services," 130

the total of columns E and F is the amount to be entered. Under 2 "Cost of goods sold" appears. 3 "Labor (see salaries and wages," line 16). 4, "Materials and supplies," is taken from column A, as is 5, "Merchandise bought for sale." The amounts for 9, "Inventories at beginning of year," and 11, the "Inventories at end of year," are found from "Summary of inventories," column 29, Fig. 12. When these allowances are made we have in line 12 the "net cost of goods sold." Line 16, "Salaries and wages," is taken from column G, Fig. 10; line 17, "Rent," is taken from column H, Fig. 10. Line 18, "Interest on business indebtedness," is taken from column J, Fig. 10. Line 19, "Taxes on business and business property," is taken from column K; line 20, "Repairs" (from column L, Fig. 10); "Wear and tear" (from column 27, Fig. 11) and "Property losses" (from column V, Fig. 10); line 21, "Bad debts arising from sales" (from column W); line 22, "Other expenses," are taken from columns M to T inclusive Fig. 10. The total other business deductions and net cost of goods sold taken from the gross sales and income from business services gives the net income from business. Fig. 14 shows the percentage statistics of the business. Referring now to Fig. 15 the normal tax and surtax may be determined from the table.

Since mistakes are liable to occur during transcribing, the fewer times transcription takes place the fewer mistakes will arise from this cause. In order to bring about this result, I may print the form similar to form 1040 United States income tax return (as shown in Fig. 13), the same size and in the same proportions as the regular form and provide a carbon sheet on the front or back of the sheet containing the form as shown in Fig. 13. By this means the form 1040 to be turned in to the Internal Revenue Bureau may be made at the same time as the same form which is a part of my book. Since the original should be turned in to the Government, I prefer to have the carbon above that part of the page containing the form as shown in Fig. 13. Attention is called to the fact that the carbon sheet, if used, may be folded back on itself one or more times to have it out of the way until needed and keep it from soiling the sheet.

If the carbon paper is not desired, the information contained in the form shown by Fig. 13 may be copied conveniently and directly to the corresponding part of the income tax return form 1040.

It will thus be seen that I have provided a book for the keeping of accounts wherein sheets are arranged for the keeping of accounts to be closed at short intervals of time such as a week, other sheets to receive the totals of such accounts in a line across

the page, and having a line for each week or short interval of time in the year, this latter sheet forming a recapitulation sheet and having its columns arranged in groups so that the permitted deductions under the 70 United States income tax return are made available for ready and easy transfer to the proper place in a form similar to the income tax return form which also forms a part of the book. 75

It is equally clear that I have provided such a system wherein the places of entry which are not for original entries contain references to the places in the book where the amounts for the entries may be found. 80

While I describe and claim my invention as a book, I desire to have it understood that I do not limit myself to a permanently bound book, since a loose leaf book can as well be used in connection with my invention. 85

I also desire to have it understood that while I have described my invention as being applied to a condition where it is desirable to have the accounts of Figs. 1 to 9 closed each 90 week, yet it is equally useful in conditions where it would be desirable to close these accounts at the end of a shorter or longer time. In this case, the number of lines on Fig. 10 could be made greater or less than 95 the 52 lines described. This is for the reason that one line of Fig. 10 is devoted to each set of accounts 1 to 9 and there are enough lines to carry the accounts for a year.

I desire also to have it understood that 100 while only one sheet is described for Fig. 1 that it may be necessary to have many such sheets to provide space for the merchandise account for the length of time it is to run such as a week. It is further to be understood that while Fig. 10 is described as a sheet, yet it may and probably will, extend over two pages and it may also be necessary to have other sheets to provide additional lines as in the case of the use of my book in 105 a business in which it was found to be desirable to balance the accounts, illustrated in Figs. 1 to 9, each three days. Obviously since 104 lines would be too many for one sheet, more than one sheet could be used. 110 115

It is to be further understood that while my invention is particularly described with relation to the present form 1040 income tax return, yet should the Government change the arrangement of items on the income tax return, it would only be necessary to replace the present form with the new form and rearrange the columns of the recapitulation sheet and in turn the items in the cash account, Fig. 7, to make my book 120 conform to any such new income tax return which might be adopted.

While I have described the preferred form of my invention in detail, I desire to have it understood that modifications and 130

changes may be made without departing from the spirit of my invention and within the scope of the appended claims.

Having described my invention, what I claim is:

1. An account book comprising correlated groups of accounts, the accounts of one of the groups having appropriate headings for the entry of data for a short period 70
10 of time, another of the groups comprising a recapitulation of the accounts of the first group, an income tax return form having indicia thereon denoting columns in the recapitulation from which the data for the income tax return are taken.
2. An account book comprising correlated groups of accounts, the accounts of one of the groups having appropriately designated lines and columns for the entry of data for a short period of time, another of the groups comprising lines and columns for the recapitulation of the accounts of the first group, an income tax return form, the columns in the recapitulation which deal 80
20 with expenses which are deducted under the income tax return being segregated, to facilitate transfer to the income tax return form.
3. An account book comprising correlated groups of accounts, the accounts of one of the groups having appropriately designated lines and columns for the entry of data for a short period of time, another of the groups comprising a recapitulation of the accounts 85
25 of the first group, the columns in the recapitulation which deal with expenses which are deducted under the income tax return, being segregated to facilitate transfer to the income tax return form, an income tax return form having indicia referring to the columns in the recapitulation from which the amounts to be entered are taken.
4. An account book comprising a series of groups of correlated accounts, the accounts 90
30 of each group having appropriately designated lines and columns for entry of data for a short period of time, a recapitulation sheet having columns appropriately designated to receive the totals of the accounts closed at the ends of the short periods of time, an income tax return form having indicia thereon opposite the several items to denote the columns in the recapitulation sheet from which the amounts for entry 100
35 thereon are to be taken.
5. An account book comprising groups of correlated accounts, the accounts of one group having appropriately designated lines and columns for the entry of data for a short period of time, a yearly recapitulation sheet having another group of accounts in appropriately designated columns to indicate the place in the first group where the amounts to be entered are to be found, there 105
40 being lines on the recapitulation sheet for the entry of amounts under the appropriate column headings and having indicia denoting the place in the first group of accounts from where the amounts of entry are to be taken, the group of accounts on the recapitulation sheet being arranged in sub-groups, one of the sub-groups having its accounts arranged in substantially the order of occurrence on the Government income tax return form.
6. An account book comprising groups of correlated accounts, the accounts of one of the groups having appropriately designated lines and columns for the entry of data for a short period of time, a yearly recapitulation sheet having another group of accounts in appropriately designated columns to indicate the place in the first group where the amounts to be entered are to be found, there 110
45 being lines on the recapitulation sheet for the entry of amounts from the first group, under the appropriate column headings, there being one such line for each such short period of time for the year, the columns of the recapitulation sheet dealing with expenses which are deductible under the income tax return being segregated to facilitate transfer to the Government income tax return.
7. An account book comprising appropriately designated lines and columns for accounts for a short period of time, recapitulation columns having indicia referring to the totals under the accounts for a short period of time, yearly accounts having columns designated by indicia referring to the totals under the recapitulation columns, the yearly accounts including a form, similar to that of the summary of business on the income tax return, each column or line not for an original entry having indicia thereon giving information as to where the entry for that column or line will be found.
8. An account book comprising appropriately designated lines and columns for accounts for a short period of time, recapitulation columns having indicia referring to the totals under the accounts for a short period of time and having a line for the entry each said short period of time of the 115
50 accounts for that period, a yearly account having indicia similar to that of the summary of business of the income tax return, each column or line not for an original entry having indicia thereon giving information as to where the entry for that column or line will be found, the columns on the recapitulation sheet showing those expenses which are deductible for income tax return in one group and those which are 120
55 not deductible for income tax in another group.
9. An account book comprising columns for accounts for a short period of time, recapitulation columns having indicia refer- 130
60

ring to the totals under the accounts for a short period of time and having a line for the entry each said short period of time of the accounts for that period, a yearly account having indicia similar to that on the summary of business of the income tax return, each column or line not for an original entry having indicia thereon giving information as to where the entry for that line will be found.

10. An account book having a set of leaves suitably ruled and appropriately designated for the reception of data relative to merchandise received and paid for, another set 15 of leaves designated to receive respectively and in succession, data for successive periods of time, each leaf having appropriately designated spaces for the reception of amounts of "net merchandise received" for 20 the relatively short period of time which this sheet is to be open, "accounts payable" covering the same period of time, "merchandise stock on hand" covering the same period of time, "record of sales" having spaces 25 for daily entry of "cash" and "charge" sales during the same period of time, "accounts receivable," "cash account" and "profit and loss account" each covering the time during which the accounts of the sheet are open, 30 a recapitulation sheet having appropriately

designated columns and having a line for the reception of data from each corresponding pair of sheets from the first two sets of sheets, the recapitulation sheet having a group of columns for the reception of entries of expenses deductible under the income tax return, said columns being arranged in order of appearance on a Government income tax return form and designated in such a manner as to facilitate 35 transfer of the totals of such columns to said income tax return form.

11. An account book comprising correlated groups of accounts, the accounts of one of the groups having appropriate headings for the entry of data for a short period of time, another of the groups comprising a recapitulation of the accounts of the first group, an income tax return form having indicia denoting columns in the recapitulation from which the amounts of the entries for the income tax return are taken, a carbon sheet above the income tax return form whereby the Government form may be placed over the form in the book and the 50 carbon copy of the original thereby retained in the book.

In testimony whereof I affix my signature.

HARRY G. CARTER.
